LIGHT-REFLECTING SIMMERING SHUTTER
FOR HIGH-PRESSURE METAL VAPOR
LAMPS

John Bernard Score Smyth, London, England, assignor to The General Electric Company, Limited, London, England

Application December 31, 1947, Serial No. 794,836
In Great Britain November 11, 1946Section 1, Public Law 690, August 8, 1946
Patent expires November 11, 1966

4 Claims. (Cl. 240—11.4)

1

This invention relates to lighting fittings suitable for lighting studios, stages and the like, where the light source is a high pressure metal vapour (H. P. M. V.) lamp, such as a high pressure mercury vapour lamp which may contain additional metallic vapours introduced to modify the colour rendering of the lamp.

It is well known that when such lamps are switched off after they have been working, some time must elapse before they can be made to relight unless relatively complicated means for re-starting are provided.

In cinema studios and for some other purposes, it is required to be able to turn the illumination on and off at will and it is one object of the present invention to provide relatively simple means whereby this can be done when the light source is a lamp of the H. P. M. V. type.

According to one aspect of the present invention, a lighting fitting suitable for lighting a studio, stage or the like, and adapted to operate with a lamp of the H. P. M. V. type includes at least one movable shutter arranged to open and close, the said shutter or shutters being arranged, when closed, to interrupt the passage of light from the lamp and to co-operate with one another and/or with one or more fixed members substantially to surround at least the bulb or the like of the lamp.

According to another aspect of the present invention a lighting fitting suitable for lighting a studio, stage or the like and adapted to operate with a lamp of the H. P. M. V. type includes at least one movable shutter arranged to open and close, the said shutter being arranged, when closed, to interrupt the passage of light from the lamp and to reflect heat radiated by the lamp back to the lamp to assist in keeping the temperature thereof sufficiently high for the vapour pressure to be maintained when power supplied to the lamp is reduced below its normal operating value.

The said shutter or shutters may form part of the optical system of the fitting.

Means may be provided for reducing the power supplied to the lamp, when the shutter or shutters are closed while the lamp is operating to a value sufficiently high for the discharge therein to be maintained. These means may be mechanically linked with the shutter or shutters so that power is automatically reduced when they are closed. Means may also be provided for cutting off the ventilation to the lamp when the movable shutters are closed in order to maintain the temperature of the lamp at a high value.

2

The illumination can therefore be turned off by moving the said parts into the closed position whilst the power to the lamp is reduced but not cut off. The illumination can be restored almost immediately by opening the said parts and restoring the full current to the lamp.

One example of a lighting fitting in accordance with the present invention will now be described by way of example with reference to the three figures of the accompanying diagrammatic drawings in which Figure 1 shows an elevation of the fitting with a side panel removed; Figure 2 shows a plan of the fitting with the top cover removed; and Figure 3 shows an electric circuit for the operation of the lamp.

Referring now to Figures 1 and 2 of the drawings, the lighting fitting 1 comprises a housing 2 carrying upper and lower lampholders 3 and 4 respectively for a H. P. M. V. lamp (not shown).

An optical reflector system is associated with the lamp and consists of a fixed centre part 5, fixed top and bottom parts 6 and 7, and hinged side parts 8 and 9. The parts 5—9 are mounted on a suitable framework (not shown) inside the housing 2. The two side parts 8 and 9 are capable of swinging about axes parallel to the axis of the lamp as hereinafter described.

When a H. P. M. V. lamp in the fitting 1 is operating and the reflector parts 8 and 9 are in the open position shown in Figure 2, all the parts 5—9 form part of the reflector system and may combine with other optical elements (not shown) to give a desired distribution of light from the lamp. When the illumination is to be turned off, the power supply to the lamp is reduced and at the same time the parts 8 and 9 are moved into the position shown 8' and 9' in Figure 2. The centre part 5 and the side parts 8 and 9 then form a three sided enclosure around the lamp which is substantially closed at each end thereof by the top and bottom reflector parts 6 and 7.

The reflector parts 8 and 9 are closed by moving a lever 10 into the open position 10'. A lever and link mechanism comprising members 11 and 12 is provided between the lever 10 and parts 8 and 9. Considerable play is provided between the parts of this mechanism and toggle springs 13 and 14 are arranged to hold the members 12 in the open or closed position of the parts 8 and 9, over a dead-centre position so that the parts 8 and 9 open or close with a snap action. Stops (not shown) may be provided to accurately locate the positions of the parts 8 and 9.

A compartment 15 located under the main housing 2 of the fitting contains ancillary elec-

tric equipment associated with the lamp. The lever 10 is arranged to operate a switch (not shown) to insert part of a ballast resistor (not shown) in the lamp circuit when the parts 8 and 9 are closed. Alternatively a separate switch may be provided to reduce the power supplied to the lamp. The compartment 15 may also contain electrical and mechanical interlocks arranged so that the main supply cannot be switched on until the parts 8 and 9 are in their closed position 9' and 9'', the interlock mechanism including a relay having an operating coil connected across the lamp, the relay being adapted to prevent the parts 8 and 9 being opened and thus cutting out part of the said ballast resistor until such time as the voltage across the lamp has reached a predetermined value.

A suitable electric circuit for operating the lamp is shown in Figure 3. A lamp 20 is supplied from an alternating current supply 21 through two resistances 22 and 23 respectively, and a starting choke coil 24 connected in series. The electric supply to the lamp is controlled by a double pole switch 25. A switch 26 is connected across the resistance 23 to enable it to be short circuited. A relay switch 27 is connected to short circuit the choke coil 24 and is operated by a winding 28 connected to carry the current flowing through the lamp 20. A starting switch 29 is arranged to short circuit the lamp and winding 28 for starting purposes.

To start the lamp the switch 25 is closed while switch 26 is open. As no current flows in the lamp under these conditions, the relay switch 27 is open. When the starting switch 29 is closed momentarily current flows through the resistances 22 and 23 and the choke coil 24. The voltage surge due to the choke coil 24 when the starting switch 29 is opened causes an electric discharge to start through the lamp 20 and draw current through the winding 28 to cause the relay switch 27 to close to short circuit the choke coil 24. While the lamp 20 is warming up to the operating temperature and pressure the switch 26 is open so that reduced power is supplied to the lamp. During this period the shutters of the fitting are closed around the lamp to conserve heat. When the lamp has reached the normal operating temperature and pressure the resistance 23 can be short circuited by the switch 26 to raise the power input to the normal level and the shutters opened to allow light to be emitted from the fitting. If it is desired to cut off the light from the lamp the shutters can be closed and the switch 26 opened to reduce the power supplied to the lamp to a value such that it maintains the lamp at or about its normal operating temperature and pressure so that it may rapidly be brought to normal operation by opening the shutters and restoring the input to the normal value.

I claim:

1. A lighting fitting comprising in combination a lamp housing, means to mount within said housing an electric lamp of the high pressure metal vapour type, at least one light- and heat-reflecting shutter, means to mount said shutter for pivotal movement in said housing between two positions in one of which the shutter allows a light beam from the lamp to leave the housing and constitutes a reflector forming at least a part of the optical system of the fitting, and in the other of which the shutter prevents light from leaving the housing and also reflects back to the lamp heat emanating from the lamp, operating

means to move said shutter between its first and second positions, circuit means for reducing power supplied to the lamp while maintaining an electric discharge through the lamp, means to render said circuit means effective when the shutter is in its second-named position, heat reflected from the shutter in such position maintaining the temperature of the lamp with the reduced power input substantially at the same temperature as with the shutter in the first-named position with normal power input to the lamp.

5 2. A lighting fitting comprising in combination a lamp housing, means to mount within said housing an electric lamp of the high pressure metal vapour type, a light- and heat-reflecting member mounted within said housing, two light- and heat-reflecting shutters, means to mount said shutters, one on each side of the first mentioned reflecting member, for pivotal movement in said housing between two positions in one of which the shutters allow a light beam from the lamp to leave the housing, and in the other of which the shutters prevent light from leaving the housing and co-operate with the first mentioned reflecting member substantially to surround at least part of the envelope of the lamp to reflect light and heat back to the lamp to maintain the vapour pressure within the lamp envelope when the current to the lamp is below its normal operating value, and operating means to move said shutters between said first and second positions.

3. A lighting fitting comprising in combination a lamp housing, means to mount within said housing an electric lamp of the high pressure metal vapour type, a light- and heat-reflecting member mounted within said housing, two light- and heat-reflecting shutters, means to mount said shutters, one on each side of the first mentioned reflecting member, for pivotal movement in said housing between two positions in one of which the shutters allow a light beam from the lamp to leave the housing, and in the other of which the shutters prevent light from leaving the housing and co-operate with the first-mentioned reflecting member substantially to surround at least part of the envelope of the lamp to reflect light and heat back to the lamp to maintain the vapour pressure within the lamp envelope when the current to the lamp is below its normal operating value, operating means to move said shutters between said first and second positions, circuit means for reducing power supplied to the lamp while maintaining an electric discharge through the lamp, and means to render said circuit means effective when the shutter is in its second-named position.

4. A lighting fitting comprising in combination a lamp housing, means to mount within said housing an electric lamp of the high pressure metal vapour type, a light- and heat-reflecting member mounted within said housing, a first pair of light- and heat-reflecting members, means to mount said first pair of light-reflecting members within said housing adjacent to two opposite sides of said first reflecting member, a second pair of light- and heat-reflecting members, means to mount each of said second pair of members for pivotal movement in said housing about axes adjacent to the other two sides of the first mentioned reflecting member, and operating means to effect rotation of the second pair of reflecting members between a first position in which they co-operate with the first-mentioned reflecting member and the first pair of reflecting members to project light from the housing, and a second

position in which the second pair of reflecting members co-operate with the first mentioned reflecting member and the first pair of reflecting members substantially enclose at least part of the envelope of the lamp to prevent light from the lamp leaving the housing and to reflect heat back to the lamp to maintain the vapour pressure within the lamp envelope when the power input to the lamp is below its normal operating value.
